CRATE FOR CAN ENDS

John Coyle, Baltimore, Md., assignor to Continental Can Company, Inc., New York, N. Y., a corporation of New York

Application July 20, 1932. Serial No. 623,645

2 Claims. (Cl. 206—46)

The invention relates to new and useful improvements in a crate for can ends, and more particularly to a crate within which unit packages of can ends may be stored for shipment.

5 An object of the invention is to provide a crate whereby the unit packages when stored within the crate and strapped together therein, are held from endwise movement and properly confined for shipment.

10 A further object of the invention is to provide a crate of the above type which may be readily knocked down and returned for subsequent use.

In the drawings which show by way of illustration one embodiment of the invention—

15 Figure 1 is a perspective view of the crate assembled and ready to receive the packages of can ends;

Fig. 2 is a view similar to Fig. 1, showing the crate partly filled with unit packages of can ends;

20 Fig. 3 is a view showing the crate as completely filled and closed ready for shipment;

Fig. 4 is a vertical sectional view through a portion of the crate with the can bodies packed therein;

25 Fig. 5 is a perspective view of a unit package of can ends;

Fig. 6 is a view in section through the package and partly in section through the ends, and

Fig. 7 is an enlarged detail showing the manner 30 of detachably connecting the angle bars.

The invention has to do with a crate for packaging can ends. The can ends are grouped and then wrapped in unit packages, each package having a predetermined number of can ends. The can ends are grouped or brought together for a unit package and are then wrapped in paper, the ends of which packages are sealed so that the unit packages may be handled and stored for shipment. The crate is of the knock-down type and is preferably made of angle bars. The angle bars are secured together by bolts so as to provide supporting base members which are spaced from each other the length of a unit package. The angle bars face each other, so that the packages

45 may be laid and supported on the horizontal members of the angle bars, and the vertical members will retain the unit packages resting thereon from endwise movement. These base members are preferably secured to blocks of wood which raise the base members from the floor and form a skid under which the arms of a truck may be slid for the lifting and moving of the crate of ends. The side members are similarly placed so as to support the packages when placed one on another,

50 and the angle bars also prevent the packages from

endwise movement. The same is true of the top angle bars. The angle bars, when joined, form two rectangular frame members, and these are connected by the skid blocks and by cross braces. After the unit packages have been placed in the 60 crate, they are covered by paper, and are bound together by the bailing band which encircles the unit packages only.

Referring more in detail to the drawings, the 65 can ends indicated at C are brought together in a predetermined number to form a unit package 1, and then a wrapper 2 is placed around the grouped ends and the ends 3 thereof folded down against the ends of the package and secured by sealing strips 4. This produces a unit 70 package which may be readily handled and which will retain the ends in their grouped units during shipment.

The crate for the unit packages is made of 75 angle bars which are similar in shape and dimensions. The angle bars 5 and 6 are placed facing each other and are secured to blocks, preferably of wood, indicated at 7 in the drawings. These angle bars are secured to the wood by screws so that they can be readily detached 80 therefrom. The blocks of wood are dimensioned so as to form with the angle bars a base member or skid on which the unit packages are stacked. This raises the angle bars so that the arms of a transfer truck may be slid beneath the 85 angle bars and the crate raised for transportation. The angle bar 6 when attached to the skid blocks provides a horizontal supporting plate or member 6^a and a vertically extending plate 6^b.

The angle bar 5 provides a vertical plate 5^b and 90 also a horizontal plate 5^a. Attached to the angle bars 5 and 6, respectively, are side angle bars 7^a and 8. The angle bars are secured together by bolts 9, 9 which can be readily removed for detaching the angle bars from each other. The 95 angle bar 8 is so placed that the side plate 8^a thereof forms an end wall for retaining the unit packages against lateral movement in the crate. It also provides a side wall 8^b which prevents the unit packages from endwise movement in the 100 crate. The angle bar 7^a operates in precisely the same manner. At the other side of the crate are side angle bars 10 and 11 which are similarly arranged and operate in a similar manner to prevent lateral movement of the unit packages, and also 105 endwise movement of the packages contacting therewith. These angle bars 10 and 11 are connected by bolts 9, 9 to the angle bars 5 and 6, respectively.

Connecting the angle bars 7^a and 8 is a cross 110

bar 12 which is secured thereto by bolts. Also connecting the side angle bars 10 and 11 is a cross brace 13. Attached to the upper ends of the angle bars 7^a and 10 is a top angle bar 14. Attached to the upper ends of the angle bars 8 and 11 is a top angle bar 15. These angle bars are secured to the end angle bars by bolts 9, 9. The top angle bars are arranged so that one face plate thereof overlies the unit packages at the upper side thereof, and the other face plate extends down over the end of the top unit packages and prevents endwise movement thereof. The unit packages 1 are placed within the crate as shown in Fig. 2. The ends of the unit packages lie substantially in a plane just inside the side plates of the bottom, end and top angle bars. The packages rest on the angle plates 5^a and 6^a. They are retained from lateral movement by the angle plates arranged similar to the angle plates 8^a, and they are prevented from endwise movement where they contact with the angle bars by the side plates similar to the plates 8^b. A strip of corrugated pasteboard or other flexible material, indicated at 16 in Figures 2 and 3, is placed around the unit packages, and encircling the unit packages and this strip of paper, is a bailing band 17. The bailing band thus ties together all of the unit packages, and holds said unit packages in such a frictional contact with each other as to prevent endwise movement of the unit packages which do not contact with the angle bars. The can ends in the unit packages provide what might be termed a serrated bearing face at the side of each unit package, and this, together with the paper wrappers, insures that the unit packages when placed will not slip endwise in the crate. The side faces of the crate are closed by sheets of corrugated board or other flexible covering material indicated at 18. This completes the package of can ends, and the crated can ends are ready for shipment. When the crate of can ends reaches its destination, and the ends have been removed therefrom, the bolts and screws may be removed and the angle bars thus knocked down and readily packed in a small compass and returned to the manufacturer, so that they may be again assembled and a crate formed for a new shipment of can ends.

It will be noted from the above that the angle bars not only confine the can ends, but will protect the same during shipment. These angle bars are all of the same length, and each angle bar has openings formed therein for the bolts or screws which secure the same to the skids, and

55

60

65

70

75

also for the cross braces. The angle bars are all of the same length, and the bolt-holes are so disposed that they are interchangeable. When the crate is knocked down and it is desirable to assemble the same, any angle bar that is picked up may be attached to the skid, and the same is true of the other angle bars, so that it is not necessary to select an angle bar for any particular place. This enables the parts to be quickly assembled in the forming of the crate. It is obvious that minor changes in the details of construction and the arrangement of the parts may be made without departing from the spirit of the invention as set forth in the appended claims.

Having thus described the invention, what I claim as new and desire to secure by Letters Patent, is—

1. A crate for can ends comprising angle bars, bolts detachably securing said angle bars to form side frame members, skid blocks detachably connecting and supporting said side frame members, cross braces detachably connecting said side frame members, unit wrapped packages of can ends supported by said angle bars, said side frame members being spaced so as to receive said unit packages, one face of each angle bar serving to support and retain said unit packages from lateral movement, and the other face of each angle bar serving to retain said unit packages from endwise movement, a protecting wrapper encircling the unit packages between the side members, a bailing band surrounding said unit packages and wrapping paper for binding together the unit packages, and a protecting flexible sheet for closing the side openings of the crate. 110

2. A crate for can ends comprising angle bars, skid blocks detachably connecting said angle bars for forming a base member, angle bars detachably connected to each end of each angle bar of the base member and forming side members, angle bars detachably connected to the angle bars of the side members and forming top members, a brace detachably connected to the angle bars of the side members adjacent the upper ends thereof, unit wrapped packages of can ends supported by said angle bars, each of said angle bars being positioned so that one face of the angle bar serves to support and retain the unit packages from lateral movement, and the other face of each angle bar serves to retain the unit packages from endwise movement, and a bailing band encircling the unit packages between the angle bars for tying the same together. 120
